UNITED STATES PATENT OFFICE.

WALTER R. BRANHAM, OF FORT VALLEY, GEORGIA.

PUSHER.

Application filed September 14, 1926. Serial No. 135,456.

This invention aims to provide novel means whereby, when the gripper of a printing press moves toward the platen, the sheet which is to be printed upon will be moved 5 over automatically, thereby obtaining a much better register than can be secured by hand, and, further, enabling the press to be operated at a higher speed than would be possible otherwise.

It is within the province of the disclosure to improve generally and to enhance the utility of devices of that type to which the invention appertains.

With the above and other objects in view 15 which will appear as the description proceeds, the invention resides in the combination and arrangement of parts and in the details of construction hereinafter described and claimed, it being understood that changes 20 in the precise embodiment of the invention herein disclosed, may be made within the scope of what is claimed, without departing from the spirit of the invention.

In the drawings:—

25 Figure 1 shows in elevation, a portion of a printing press wherewith the device forming the subject matter of this application has been assembled;

Figure 2 is a detail enlarged from Figure 1;

Figure 3 is a diagrammatic cross section showing the invention as it appears when the gripper is spaced at considerable distance from the platen;

35 Figure 4 is a sectional diagrammatic view showing parts as they will appear after the gripper has moved toward the platen, from the position delineated in Figure 3.

In Figure 1 of the drawings, there is 40 shown the platen 1 of a printing press, the tympan sheet being omitted. The left gripper is shown at 3, and the right gripper at 2. The grippers 2 and 3 are secured adjustably, as at 4, to a slotted support 5 which is mounted pivotally at 6 on the platen. The construction above described is common and well known and no novelty is claimed for it, saving in so far as the parts specified may enter into combination with parts herein- 45 after described. The sheet 9 which is to be printed upon lies between the grippers 2 and 3 and the platen 1 and cooperates with the lower gages 7 and with the left gage 8, in a way well understood by those skilled in 50 the art.

The pusher arm 10 is disposed transverse-

ly of the right gripper 2 and may be constructed in a variety of ways, without departing from the spirit of the invention. The arm 10 extends between the gripper 2 and the 60 platen and has an inclined portion 11 provided with an angularly disposed end or finger 12. The gripper 2 has an opening for the reception of the end 12 under circumstances to be pointed out hereinafter. In the 65 present instance, but not of necessity, the opening for the reception of the part 12 is an elongated slot 14 in the gripper 2, although some other construction might be employed at this point.

Any suitable means may be employed for mounting the arm 10 on the gripper 2 for swinging movement. If preferred, the pusher arm 10 may have a hub 20 mounted on a shaft 15, the ends of which are received in knuckles 16 on one end of a carrier 17 (preferably a plate) superposed on the gripper and supplied at its corners with underlying spring fingers 18 which engage the inner surface of the gripper 2. The construction is such that the carrier 17 will be held frictionally against movement on the gripper under all ordinary operating conditions: but, by the application of considerable force to the carrier 17, the carrier, and 80 the pusher arm 10, may be adjusted lengthwise of the gripper 2. Spacers 22 are mounted on the shaft 15 between the hub 20 of the pusher arm 10 and the knuckles 16. The hub 20 carries a stop 21 which overhangs the 85 carrier or plate 17 and has functions which will be brought out hereinafter. The plate 17 has an opening 19 which registers with the elongated slot 14 in the gripper 2, should the gripper be provided with such a slot.

Let it be supposed that the gripper 2 is at some considerable distance from the platen 1, as disclosed in Figure 3. Under such circumstances, the stop 21 engages the carrier 17 and holds the arm 10 at such an angle 95 to the platen 1 that, when the gripper 2 moves toward the platen, from the position of Figure 3, to the position of Figure 4, the angle formed by the part 11 of the arm 10 and by the end 12, will engage the edge 105 of the sheet 9 and push the sheet over to the left, against the gage 8. The part 10 may have some resiliency, especially at the angle shown at 23, and sometimes the arm may flatten out from the position shown in 110 Figure 4, the end 12 of the arm entering still further into the slot 14 of the gripper 2

and, possibly, into the opening 19 of the carrier plate 17. As the gripper 2 moves away from the platen 1, the arm 10 assumes the position shown in Figure 3, the stop 21 co-operating with the carrier plate 17 to maintain the arm 10 at the proper angle with respect to the platen 1.

The device is simple in construction but it affords a means whereby a sheet to be printed upon may be slid over into proper register. Accuracy and neatness in the work is promoted, and production may be increased, by the use of the device forming the subject matter of this application.

15 What is claimed is:—

1. The combination with the platen and the gripper of a printing press, of a feeder arm adapted to ride along the platen as the gripper approaches the platen, and means 20 for mounting the arm intermediate its ends on the gripper for swinging movement transversely of the gripper, one end of the arm forming a stop to hold the other end of the arm at an acute angle to the platen when the

gripper is spaced from the platen and when 25 the arm is in an inoperative position.

2. The combination with the platen and the gripper of a printing press, of a feeder arm adapted to ride along the platen as the gripper approaches the platen, means for 30 mounting the arm intermediate its ends on the gripper for swinging movement transversely of the gripper, and for adjustment longitudinally of the gripper, one end of the arm forming a stop to hold the other end of the arm at an acute angle to the platen when the gripper is spaced from the platen and when the arm is in an inoperative position, and an angularly disposed finger on 35 said other end of the arm, the finger aiding to form a shoulder against which the material abuts, the gripper having an elongated slot in which the finger is received when the arm is adjusted longitudinally of the gripper.

40 In testimony that I claim the foregoing as my own, I have hereto affixed my signature.

45 WALTER R. BRANHAM.
